UNITED STATES PATENT OFFICE

163,055

SWATCH CUTTING MACHINE OR THE LIKE

Richard C. Maxant, Ayer, Mass.

Application March 3, 1950, Serial No. 8,303

Term of patent 14 years

(Cl. D55—1)

To all whom it may concern:

Be it known that I, Richard C. Maxant, a citizen of the United States, residing at Ayer, in the county of Middlesex and State of Massachusetts, have invented a new, original, and ornamental Design for Swatch Cutting Machines or the like, of which the following is a specification, reference being had to the accompanying drawings, forming part thereof.

Fig. 1 is a perspective view of a swatch cutting machine embodying my new design;

Fig. 2 is a top plan view thereof; and

Fig. 3 is an end elevation thereof.

The dominant features of the design reside in the portions shown in full lines.

I claim:

The ornamental design for a swatch cutting machine or the like, substantially as shown and described.

RICHARD C. MAXANT.
